(57) **CLAIM**

The ornamental design for an earphone case, as shown and described.

DESCRIPTION

FIG. 1 is a front perspective view of an earphone case, showing a first embodiment of our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a right side perspective view thereof;

FIG. 10 is a right side perspective view thereof, shown in an environmental use;

FIG. 11 is a left side perspective view thereof, shown in an environmental use;

FIG. 12 is a front perspective view of an earphone case, showing a second embodiment of our new design;

FIG. 13 is a front view thereof;

FIG. 14 is a back view thereof;

FIG. 15 is a top view thereof;

FIG. 16 is a bottom view thereof;

FIG. 17 is a right side view thereof;

FIG. 18 is a left side view thereof;

FIG. 19 is a back perspective view thereof;

FIG. 20 is a right side perspective view thereof;

FIG. 21 is a right side perspective view thereof, shown in an environmental use;

FIG. 22 is a left side perspective view thereof, shown in an environmental use;

FIG. 23 is a front perspective view of an earphone case, showing a third embodiment of our new design;

(Continued)

FIG. 24 is a front view thereof;
 FIG. 25 is a rear view thereof;
 FIG. 26 is a top view thereof;
 FIG. 27 is a bottom view thereof;
 FIG. 28 is a right side view thereof;
 FIG. 29 is a left side view thereof;
 FIG. 30 is a back perspective view thereof;
 FIG. 31 is a right side perspective view thereof;
 FIG. 32 is a right side perspective view thereof, shown in an environmental use; and,
 FIG. 33 is a left side perspective view thereof, shown in an environmental use.
 The broken lines in the drawings show portions of the earphone case and environmental subject matter in the depiction of earphones that form no part of the claimed design.
